UNITED STATES PATENT OFFICE.

JAMES LEROY MOUNT, OF CHICAGO, ILLINOIS.

DESIGN FOR TRAFFIC SIGNAL FOR AUTOMOBILES.

Application filed September 18, 1925. Serial No. 14,814. Term of patent 7 years.

To all whom it may concern:

Be it known that I, JAMES L. MOUNT, a citizen of the United States, residing in Chicago, in the county of Cook and State of Illinois, have invented a certain new, original, and ornamental Design for Traffic Signal for Automobiles, of which the following is a specification, reference being had to the accompanying drawing, forming a part thereof.

Figure 1 is an elevational view of the design, and

Fig. 2 is a plan view thereof.

I claim:

The ornamental design for traffic signal for automobiles, substantially as shown.

JAMES LEROY MOUNT.
